Primary Examiner — Kevin Rudzinski(74) *Attorney, Agent, or Firm* — Wong, Cabello, Lutsch, Rutherford & Bruculeri, LLP.(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

The FIGURE is a front view of a display screen with graphical user interface showing my new design.

The broken line showing of portion of the display screen and the text is for environmental purposes only and forms no part of the claimed design.
